Primary Examiner — Cynthia Underwood(74) *Attorney, Agent, or Firm* — Alan D. Kamrath;
Kamrath IP Lawfirm, P.A.(57) **CLAIM**

The ornamental design for swivel tool head, as shown and described.

DESCRIPTION

FIG. 1 is a perspective view of swivel tool head showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the swivel tool head that form no part of the claim. The dot-dash-dot lines represent a boundary of the claim and form no part of the claim.
